[57] ABSTRACT

In an electronic scan modular antenna system operating at frequency F , a circuit supplies the n modules (where n is an integer) forming the antenna with n respective synchronization signals. The circuit comprises wave generating means supplying two component signals in phase quadrature in respect of each other, of frequency $f=F/p$ (where p is an integer), respective means varying respectively the amplitudes of said component signals as functions of the desired direction of radiation of the antenna beam axis, an adder forming the sum of the output signals of the amplitude varying means, n respective fixed gain attenuating means for attenuating said sum, n adding means for respectively adding the n output signals of said n attenuating means with one of said components, and multiplying means coupled respectively to the adding means outputs and supplying said synchronization signals.

ELECTRONIC-SCAN ANTENNA

The present invention relates to electronic-scan antennas using active modules.

It is well known that such antennas comprise a plurality of elements or modules of identical structure, each including in particular at least one microwave power generator element, such as an elementary oscillator or amplifier, and that it is necessary to supply these with respective low-power reference signals having an identical frequency but respective different phases.

These reference signals are obtained from a single initial signal and as many variable phase-shift devices (phasemeters or diode logic systems) as there are modules, associated with as many phase control circuits and a phase computer.

In known devices, the phasemeter devices must cover the full range of phase variation (2π) of the radiator elements of the modules with which they are associated. In the case of directional antennas, where the beam has to scan a substantial sector, say of 90° , this results in very high cost equipment as soon as the number of modules is great (currently this number is for example 100 and even more).

It is an object of the present invention to reduce the complexity of the phase control arrangement.

According to the invention there is provided an electronic scan antenna system comprising n modules M_i ($i = 1, 2, \dots, n$) and a circuit supplying the modules with n respective reference signals S_i of frequency F_1 , said circuit comprising:

means for supplying a first and a second component signals of identical frequency $f = F_1/p$, where p is an integer greater than one, said signals being in phase quadrature in respect of each other, said means having a first output for said first signal and a second output for said second signal;

a controllable amplitude modifying device having a signal input coupled to said second output, a control input and a third output;

n fixed gain amplitude modifying devices having respective inputs, coupled in parallel, to one of said second and third outputs, and respective outputs;

n respective adders having respective first inputs coupled respectively to said outputs of said n fixed gain modifying devices, respective second inputs coupled to that one of said second and third outputs which is not coupled to said n modifying devices, and respective outputs;

respective frequency multipliers producing frequency multiplication by p , having respective inputs coupled to said adder outputs and n outputs supplying respectively said reference signals;

and control means for controlling said controllable amplitude modifying means, said control means having an output coupled to said control input.

For a better understanding of the invention and to show how the same may be carried into effect, reference will be made to the drawings accompanying the ensuing description and in which:

FIGS. 1, 2 and 3 illustrate by way of a reminder, a known modular antenna and the essential elements of examples of active modules, with which the invention is concerned;

FIGS. 4 and 5 illustrate respectively block diagrams of two circuits for generating reference signals in an

electronic-scan antenna using active modules, in accordance with the invention;

FIG. 6 is an explanatory diagram and FIGS. 7 and 8 are general block diagrams of improved electronic-scan antennas in accordance with the invention.

Throughout the description, like references are used for denoting like elements

Known electronic-scan antennas with active modules, operating at a frequency F , essentially comprise a master generator P, FIG. 1, producing a pilot signal S of frequency F , n generally identical modules, $M_1, M_2, \dots, M_n$, and n phasemeter devices $D_1, D_2, \dots, D_n$. In certain antennas, the phasemeter devices are incorporated in the respective modules with which they are associated. In all cases, a phase computer C, or a memory device, supplies to n phase control devices C_1 to C_n , the values of the phases to be applied to devices D_1 to D_n respectively, as a function of the angle θ of the radiation direction.

Whether they form an integral part of the modules or not, or, again, are constituted by phasemeter devices or by diode logic systems, the phasemeter elements D_i ($i = 1, 2, \dots, n$), in all cases, supply n respective reference signals $S_1, S_2, \dots, S_n$ of frequency F , which are phase shifted with respect to the master signal by ϕ_i ($i = 1, 2, \dots, n$), a quantity which may range between 0 and 2π .

Depending upon whether the modules incorporate oscillators or amplifier circuits, as power generators, the signal S and, consequently the signals S_i ($i = 1, 2, \dots, n$), will have a higher or lower power, but in all cases they will have a very low power compared with that radiated by the modules.

In FIG. 1, continuous lines illustrate the coupling between the modules and the master generator, but, of course, the coupling could be effected by radiation in the case of modules including respective oscillators.

If the antenna is also used for reception, a duplexer located between the phasemeter devices and the receiver, ensures that the transmitted and receiver signals are correctly switched.

The invention relates to active module antennas in which the phasemeter devices are not incorporated in the modules themselves.

By way of reminder, FIG. 2 illustrates an example of a known active module in the case where simultaneous transmission and reception are possible; the module then essentially comprises:

a transmitter oscillator OE of frequency F_1 , whose phase is controlled by a synchronisation signal SE of frequency F_1 , through a phase loop PE essentially embodying a phase detector DE and an amplifier AE; the signals produced by the oscillator OE can, if required, be amplitude-modulated by an external signal Σ ;

a local oscillator OR of frequency F_2 which differs from F_1 , whose phase is controlled by a synchronisation signal SR of frequency F_2 , through a phase loop PR essentially comprising a phase detector DR and an amplifier AR;

a mixer MR with one input coupled to the oscillator OR and another input coupled to the "reception" terminal of the duplexer DR, which in turn is coupled to the antenna and to the oscillator OE.

The intermediate frequency signals at the output of the mixer MR are amplified in the amplifier AI which is coupled to the receiver R.

If transmission and reception are not simultaneous (which is the most general case), a single oscillator can be used as shown in the diagram of FIG. 3, where SW_1 and SW_2 are switches which are synchronised with the duplexer, and R_s a grounding resistor for switch SW_2 .

The object of the invention is precisely the supply of the signals SE and SR ; these signals are similar to the signals S_i of FIG. 1.

The signals SE and SR are generally of the same power and may be possibly obtained from the same master generator.

In all cases, the signals S_i , whether used for transmission (signals similar to SE) or for reception (signals similar to SR), are obtained in accordance with the invention from a master generator output signal of lower frequency f equal to F/p (F being equal to F_1 or F_2 as the case may be), and, a control device.

Respective intermediate reference waves S'_i of frequency F/p , are obtained for each module by the addition of two components which are in phase quadrature with respect to each other, the amplitude of at least one said components being modified (attenuated or amplified) as a function of the angle of the desired radiation direction (and this modification being the same for all the modules), and at least one of said two components being furthermore subjected to a fixed modification (attenuation or amplification) which is different for each module. The signals S_i are then obtained from the signals S'_i by frequency multiplication.

In the following for the sake of brevity, it is assumed that the amplitudes are only attenuated.

FIG. 4 illustrates the block diagram of a circuit for generating the signals S_i in accordance with the invention : A signal generator G supplies two component waves V_1 and V_2 of identical frequency f , which are phase-shifted with respect to each other by $\pi/2$; for example, generator G may be an oscillator, of frequency $f = 115$ Mc/s with outputs which are in quadrature, or be built up by an oscillator and a phase-splitter in series. The two component waves respectively illustrated by the vectors $\vec{V}_1$ and $\vec{V}_2$ in FIG. 6 are respectively applied to the input signals of amplitude modifying devices, for example variable-gain attenuators AV_1 and AV_2 , whose gain vary as a function of the desired radiation direction $\mathbf{0}$. To this end, a computer Ca , or a memory device (when the values of θ remains fixed) supplies, to the devices CG_1 and CG_2 controlling the gain of the attenuators, the appropriate gain value indication as a function of θ .

The output of the attenuator AV_1 , producing the signal $K_1 V_1$ and the output of the attenuator AV_2 , producing the signal $K_2 V_2$, are coupled respectively to the inputs of an adder AD , the output of which is directly coupled in parallel to the inputs of n attenuators AT_i ($i = 1, 2, \dots, n$); the outputs of these attenuators AT_i are coupled respectively to the first inputs of n adders AD_i ($i = 1, 2, \dots, n$); the respective second inputs of adders AD_i are fed with signal V_1 (and, more generally, with one of signals $V_1, V_2, K_1 V_1$ or $K_2 V_2$).

The outputs of the adders are connected to respective frequency multipliers X_i ($i = 1$ to n). For an odd value of n , the first input of the central adder [$i = n + 1/2$] is not supplied and this adder can be discarded.

This phase-shifting method is of particular interest in the case of a transmit-receive antenna, since it is carried out simply by means of attenuators and adders,

that is to say elements which can be operated at two distinct frequencies.

It is recalled that the phase, in relation to that of signal V_1 , of the signal (illustrated by vector $\vec{V}$ in FIG. 6) obtained by the addition of the two signals $K_1 V_1$ and $K_2 V_2$ varies between zero for $K_2 = 0$ and $\pi/2$ for $K_2 = 0$, as a function of K_2/K_1 ; 1 amplitude is equal to $|V_1 \sqrt{K_1^2 + K_2^2}$ where $|V_1| = |V_2|$; the phase of the signal obtained by the addition of signal V_1 to the latter sum multiplied by coefficient r_i in the attenuator AT_i is $\tan^{-1}(K_2 r_i / 1 + K_1 r_i)$. FIG. 5 is the block diagram of a simplified embodiment of the invention ; it is assumed here that the two components are obtained by means of a phase splitter MD which is fed by a stable oscillator 0 and that the radiating elements of the modules are symmetrically arranged; since symmetrical elements are phase shifted by the same values of opposed signs ($\phi_i = -\phi_{n+1-i}$), the phase-shifts ϕ_i and $-\phi_i$ are obtained respectively by means of the same signal in phase with the oscillator and of opposite signals in quadrature; therefore, the attenuator of signal V_2 , shown at AV_3 comprises two symmetrical outputs supplying the signals $K_2 V_2$ and $-K_2 V_2$. It is also assumed here that $K_1 = 1$: the variable attenuator of signal V_1 is discarded and signals $K_2 V_2$ or $-K_2 V_2$ are directly applied to the inputs of the n attenuators AT_i .

If n is even, the signals $K_2 V_2$ are applied to $n/2$ attenuators $AT_1, \dots, AT_{n/2}$ and the signals $-K_2 V_2$ to the attenuators $AT_{n/2+1}, \dots, AT_n$. If n is odd, the signal $K_2 V_2$ supplies the attenuators $AT_1, \dots, AT_{(n-1)/2}$ and the signal $-K_2 V_2$ the attenuators $AT_{(n+3)/2}, \dots, AT_n$. Of course it is possible to form exclusively the signal $K_2 V_2$ as in FIG. 4 and then to use negative gain attenuators for half the attenuators AT_i .

FIG. 7 is the most general block diagram of a transmit/receive electronic-scan antenna comprising active modules, in accordance with the invention.

Two identical assemblies E_1 and E_2 , operating at different frequencies of f_1 and $f_2 = f_1 - f_1$ (or $f_1 + f_1$), f_1 being the intermediate frequency utilised, respectively supply the signals $K_1 V_1, K_2 V_2$ and, as the case may be, $-K_2 V_2$, with the frequencies F_1 and F_2 .

The signals are applied to two sets of attenuators, adders and multipliers, B_1 and B_2 , having respective structures identical to the sets AT_i, AD, AD_i and X_i of FIG. 4 or 5.

The outputs of the set B_1 are coupled to the transmission reference inputs of the modules M_1 and those of the set B_2 to the reception reference inputs of the latter.

A single reference input in each module is used if the modules are equipped with means for switching signals of frequency f_1 and f_2 to appropriate circuits, or if it is not intended that the antenna carry out simultaneously transmission and reception ; in this latter case, the antenna will be provided with a single set, identical to B_1 and B_2 , and a device for switching between E_1 and E_2 .

If f_2 does not exceed f_1 by more than about one-tenth of f_1 , it is also possible to utilise the same phase-splitter for the two frequencies f_1 and f_2 , as shown in FIG. 8 where a switch SW selectively couples oscillators O_1 and O_2 to the phase-splitter MD , which is coupled to a single circuit Bo comprising the various elements shown in FIG. 4 downstream the signal generator G or in FIG. 5 downstream the phase-splitter MD .

For example, in the case of an antenna system with $n=37$ modules, and a radiating frequency $F = 9,200$

Mc/s, the frequency f may be taken equal to $f = F/p = 9,200/80 = 115/\text{Mc/s}$.

For a maximum scan angle $\phi_{\text{Max}} = \pm 30^\circ$, the maximum phase shift angle at frequency f is $\phi_{\text{Max}} = [\lambda(n-1)d/2]\sin\theta_{\text{Max}}$, where d is the spacing between two adjacent sources and λ the operating wavelength. Assuming $d = 0.56\lambda$, $\phi_{\text{Max}} \approx 10\pi$ and the corresponding maximum phase shift angle at frequency f is $\alpha_{\text{Max}} = \phi_{\text{Max}}/80 = 22.5^\circ$.

In the case of a single controllable attenuator, for example AV_2 , the amplitude modifying coefficients r_i are given by the relation $t_g\alpha_i = r_i K_2$ where α_i are the phase shift angles at frequency f ; for $\theta = \theta_{\text{Max}}$, i.e., with $r_i = 1$ and $\alpha_i = \alpha_{\text{Max}}$, $K_2 = t_g\alpha_{\text{Max}}$ for n odd, which is the case here $\alpha_i = (n+1-2i)/(n-1)\alpha_{\text{Max}}$

$$r_i = \frac{t_g \left(\frac{n+1-2i}{n-1} \alpha_{\text{Max}} \right)}{t_g \alpha_{\text{Max}}} =$$

$$\frac{t_g \left(\frac{19-i}{18} \cdot 22.5 \right)}{t_g 22.5}$$

For a radiating direction defined by θ where $\theta < \theta_{\text{Max}}$, the value $\alpha_i = 1/80 [2\pi/\lambda 18.056\lambda \sin\theta] = \pi/4 \sin\theta$ is computed, which gives $K_2 = t_g\alpha_i$. The computation of K_2 may be carried out for each desired value of θ in a computer, for example a digital computer associated with the antenna and coupled to a digital analog converter which supplies a voltage which may be applied to the control input of a diode attenuator for example. The following table gives the values of the phase error due to the non linearity of the tangent function, for some values of i ;

that these errors are smaller than $\pm 8^\circ$; if errors up to $\pm 10^\circ$ can be accepted the scan angle can be extended up to $\pm 40^\circ$.

If necessary, these errors can be reduced through using two controllable attenuators as described, and shown FIG. 4; in this case $t_g\alpha_i = (r_i K_2)/(1+r_i K_1)$, K_2 and K_1 satisfying the relation $K_2/(1+K_1) = t_g\alpha_i$, it results that $t_g\alpha_i = [r_i(1+K_1)t_g\alpha_i]/[1+r_i K_1]$, which is a function of K_1 .

Self-evidently, the invention is not limited to the embodiments described and illustrated here purely by way of example.

In particular, the second inputs of adders AD_1 in FIG. 4 can be fed as well with the signal $K_1 V_1$ as with the signal V_1 , the values of K_1 , K_2 and r_i being then determined so that $t_g\alpha_{\text{Max}} = K_2/2K_1$ and $t_g\alpha_i$ being then equal to $[r_i K_2/K_1(1+r_i)]$ where two attenuators AV_1 , AV_2 are used; the method of producing reference waves in accordance with the invention, could also be combined with conventional phaseshift methods, by grouping the modules; for example if $n = 9$, the modules can be grouped in three, three waves of different phases can be derived from the wave of frequency f , and each of these dealt with in the manner indicated with reference to FIGS. 4 and 5.

What is claimed is:

1. An electronic scan antenna system, comprising n modules M_i ($i = 1, 2 \dots n$) and a circuit supplying the modules with n respective reference signals S_i of frequency F_i , said circuit comprising:

component signal supply means for supplying a first and a second component signal (V_1, V_2) of identical frequency $f = F_i/p$, where p is an integer greater than one, said signals being in phase quadrature in respect of each other, said means having a first out-

$\phi_{\text{max}} = 22.5^\circ$				$\phi'_{\text{max}} = \frac{1}{2}\phi_{\text{max}}$				
i	α_i	$K_2 r_i$	r_i	$r_i K_2$	α_i	theoretical	$\Delta\alpha_i$ (deg.)	$80\Delta\alpha_i$
1	22.5	0.414	1	0.199	11.25	11.25	0	0
3	20	.364	0.879	.175	9.92	10	0.08	6.4
5	17.5	.316	.763	.152	8.65	8.75	.1	8
7	15	.270	.652	.130	7.4	7.5	.1	8
9	12.5	.222	.519	.107	6.1	6.25	.15	12
11	10	.176	.425	.0846	4.8	5	.2	16
13	7.5	.132	.319	.0634	3.6	3.75	.15	12
15	5	.0875	.212	.0423	2.4	2.5	.1	8
17	2.5	.043	.104	.0207	1.18	1.25	.07	5.6

Since the values of r_i are computed for $\theta = \theta_{\text{Max}}$, these values are not true for another value of θ , in particular for the smallest values of θ where the tangent function is similar to a linear function.

The second column gives the values of α_i for the maximum scan angle $\theta_{\text{Max}} = \pm 30^\circ$. The third column gives $t_g\alpha_i = K_2 r_i = r_i t_g\alpha_1$ and the fourth column gives $r_i = t_g\alpha_i/t_g\alpha_1$. The fifth and sixth columns give $t_g\alpha_i$ and α_i for a scan angle $\theta < \theta_{\text{Max}}$ with, for example a maximum phase shift $\phi'_{\text{Max}} = \frac{1}{2}\phi_{\text{Max}} = 11.25 = \alpha_i$. Then $K_2 = t_g\alpha_1 = 0.199$. $t_g\alpha_i$ is computed with $K_2 = 0.199$ and the values of r_i of the fourth column, that gives the correspondant values of α_i . The seventh column gives the theoretical values of α_i which are half the values of the second column. Then the two last columns give the phase shift errors $\Delta\alpha_i$ and $\Delta\phi_i = 80\Delta\alpha_i$. It may be seen

put for said first component signal and a second output for said second component signal; a controllable amplitude amplifying device (AV_1) having a signal input coupled to said first output, a control input and an output; further adding means (AD) having a first input connected to said output of said controllable amplitude amplifying device (AV_1), a second input and an output, n fixed gain amplitude modifying devices ($\text{AT}_1, \text{AT}_2 \dots$) having respective inputs, coupled in parallel, to said output of the further adding means (AD), and respective outputs; n respective adders (AD_1, AD_2) having respective first inputs coupled respectively to said outputs of said n fixed gain modifying devices, respective sec-

ond inputs coupled in parallel to said first output and respective outputs; respective frequency multipliers ($X_1, X_2 \dots$) producing frequency multiplication by p , having respective inputs coupled to said adder outputs and n outputs supplying respectively said reference signals; and control means (CG_1) for controlling said controllable amplitude modifying means, said control means having an output coupled to said control input; wherein said circuit further comprises further control means (CG_2) having an output, further controllable amplitude modifying means (AV_2) having a control input coupled to said output of said further control means, a signal input coupled to said second output, and an output connected to the second input of said further adding means (AD) and further comprising a circuit for supplying said modules with n respective reference signals of frequency F_2 , said circuit having a structure identical to that of said circuit supplying said signals of frequency F_1 , with the exception that said component signals supply means supply signals of frequency $f_2 = F_2/p$.

2. An antenna system according to claim 1 wherein said component signal supply means of said circuits comprise respectively in series respective reference oscillators and respective phase-splitters.

3. An antenna according to claim 2, wherein all the elements of said two circuits are common with the exception of said oscillators, said antenna system further comprising a switch between said oscillators and said common phase-splitter, selectively coupling one of said oscillators to said phase-splitter

4. An electronic scan antenna system, comprising n modules M_i ($i = 1, 2, \dots, n$) and a circuit supplying the modules with n respective reference signals S_i of frequency F_1 , said circuit comprising:

component signal supply means for supplying a first and a second component signal (V_1, V_2) of identical frequency $f = F_2/p$, where p is an integer greater than one, said signals being in phase quadrature with respect to each other, said means having a first output for said first component signal and a second output for said second component signal;

a controllable amplitude amplifying device (AV_1) having a signal input coupled to said first output, a

control input and an output; further adding means having a first input connected to said output of said controllable amplitude amplifying device (AV_1), a second input and an output. 5 n fixed gain amplitude modifying devices ($AT_1, AT_2 \dots$) having respective inputs, coupled in parallel, to said output of said further adding means and respective outputs; n respective adders ($AD_1, AD_2 \dots$) having respective first inputs coupled respectively to said outputs of said n fixed gain modifying devices, respective second inputs coupled in parallel to said second output, and respective outputs; respective frequency multipliers ($X_1, X_2 \dots$) producing frequency multiplication by p , having respective inputs coupled to said adder outputs and n outputs supplying respectively said reference signals; and control means (CG_1) for controlling said controllable amplitude modifying means, said control means having an output coupled to said control input; wherein said circuit further comprises further control means (CG_2) having an output, further controllable amplitude modifying means (AV_2) having a control input coupled to said output of said further control means, a signal input coupled to said second output, and an output connected to the second input of said further adding means; and further comprising a circuit for supplying said modules with n respective reference signals of frequency F_2 , said circuit having a structure identical with that of said circuit supplying said signals of frequency F_1 , with the exception that said component signals supply means supply signals of frequency $f_2 = F_2/p$.

5. An antenna system according to claim 4, wherein said component signals supply means of said circuits comprise respectively in series respective reference oscillators and respective phase-splitters.

6. An antenna system according to claim 5, wherein all the elements of said two circuits are common with the exception of said oscillators, said antenna system further comprising a switch between said oscillators and said common phase-splitter, selectively coupling one of said oscillators to said phase-splitter.
